UNITED STATES PATENT OFFICE

2,047,008

LIQUID IMMERSSED ELECTRIC CIRCUIT
INTERRUPTERDavid Reginald Davies, Didsbury, England, as-
signor to General Electric Company, a corpo-
ration of New YorkApplication January 11, 1934, Serial No. 706,193
In Great Britain January 24, 1933

3 Claims. (Cl. 200—150)

This invention relates generally to liquid immersed circuit interrupters, that is to say circuit interrupters in which the contacts between which the circuit is interrupted are immersed in insulating liquid such as oil for the purpose of extinguishing arcing at the contacts incidental to interruption of the circuit, and relates particularly to circuit interrupters of the kind in which means is provided for setting up a magnetic field to act on the arc so as to assist the insulating liquid in extinguishing the arc.

5

A principal object of my invention is the provision of an improved circuit interrupter of the aforesaid type which shall be efficient and positive 10 in its interrupting action and simple in construction.

According to the present invention, a liquid immersed circuit interrupter is provided with a coil connected in series with the arc contacts 15 and mounted on a part of the circuit interrupter carrying the moving contact so as to be adjacent to, and have its magnetic axis disposed transversely of, the path of movement of the moving contact, and therefore of the arc itself, whereby 20 a component of force due to the combined magnetic field set up by the coil current and the arc current acts on the arc substantially at right-angles to the path thereof tending to move the arc bodily away from the circuit interrupter 25 contacts.

Conveniently, in the case of a circuit breaker of the double-break type in which the moving contacts are provided at the ends of a bridging member, the coil may be located on, or preferably be wound upon, said bridging member, and connected between the said contacts. If desired, 30 said bridging member may be provided with a magnetic core or may be formed in part of magnetic material thereby to have the effect of concentrating or directing the magnetic field set up by the coil when energized.

The invention may be applied with advantage in connection with liquid immersed circuit interrupters having provision for supplying to the arc 35 a blast of liquid and/or gas in a direction substantially transverse to the path of the arc, such for instance as is provided by the arrangements, examples of which are described in Gustaf A. Juhlin, United States Patent No. 1,902,507 for 40 Electric circuit interrupters granted March 21, 1933, and an application Serial No. 622,780 filed by Ehrenberg et al. July 15, 1932 for Electric circuit interrupters, wherein the moving contact during the opening of the circuit travels through 45 one or more passages arranged transversely to

the path of movement of the contact and through which passages a blast of liquid and/or gas is caused to pass in a direction substantially perpendicular to the direction of movement of said contact. In such application the circuit interrupter will be arranged so that the blast of liquid and/or gas acts to assist the said component of force due to the magnetic field set up as aforesaid, in blowing out the arc.

5

In another construction of liquid immersed circuit interrupter according to the invention the moving contact is arranged during the opening of the circuit interrupter to move through a passage from which one or more transverse passages extend in the direction of movement of the arc 15 caused by the aforesaid magnetic field, said transverse passages being preferably designed to permit the escape of the arc gases turbulently into the ambient liquid.

My invention will be more fully set forth in the 20 following description referring to the accompanying drawing, and the features of novelty which characterize my invention will be pointed out with particularity in the claims annexed to and forming a part of this specification.

25 Referring to the drawing, Figure 1 is an elevational view, partly in section, of a double-break circuit interrupter constructed in accordance with the invention.

Fig. 2 is a combined view to an enlarged scale 30 showing in plan the bridging member of the circuit interrupter illustrated in Fig. 1 and in section one form of arc extinguishing structure which is associated with the stationary contacts of the circuit interrupter.

35 Fig. 3 is an explanatory diagram to indicate the forces acting on the arc due to the magnetic fields set up.

Fig. 4 is an elevational view of a portion of one 40 form of arc extinguishing structure associated with the stationary contacts of the circuit interrupter, and

Fig. 5 is a plan view showing the form of a plate or grid constituting part of the arc extinguishing structure illustrated in Fig. 4, the form 45 of another grid constituting part of the arc extinguishing structure being shown in Fig. 2.

In the circuit breaker shown in Fig. 1, the housing or tank 1 supports insulating conductor bushings 2 and 3 at the depending ends of which 50 are the stationary contacts 4 and 5 respectively. The moving contacts 6 and 7 are mounted on the ends of a bridging member indicated generally at 8, which bridging member is connected by an operating rod 9 with the lifting mechanism 10 55

supported from the wall of the circuit breaker housing 1, whereby the contacts 6 and 7 can be moved into and out of engagement with their respectively associated stationary contacts 4 and 5. In the form shown, the moving contacts 6 and 7 are pivotally mounted on the bridging member 8 and are provided with biasing springs 11 and 12 respectively, for controlling the pressure between said contacts and their co-operating stationary contacts. A body of oil or other insulating liquid designated 13, is maintained in the circuit interrupter tank or housing 1 at a level completely to submerge the contacts. To assist in the extinction of the arc the stationary contacts 4 and 5 are provided with arc extinguishing structures 14 and 15 respectively, which are more fully referred to hereinafter.

As represented in Fig. 2, the bridging member 8 comprises two spaced insulating members 18 and 19 which serve to support the hinged contacts 6 and 7 respectively, and an insulating tubular member 20, to which said members 18 and 19 are secured. On the member 20 there is wound a coil or helix 21 of good electrically conducting material and this coil is electrically connected at its ends with the moving contacts 6 and 7 respectively. As thus arranged, the coil 21 will have its magnetic axis disposed transversely of the path of movement of the contacts 6 and 7.

Referring to the explanatory diagram in Fig. 3, and assuming that the current in the arc formed when the moving contact 6 is dissociated from the co-operating stationary contact 4 flows in the direction away from the contact 4 as indicated conventionally by the arrow tail at 22 and that the current in the arc formed when the moving contact 7 is dissociated from the stationary contact 5 flows in the direction towards the contact 5 as indicated by the arrow head 23, a magnetic field will be set up acting in the direction indicated by the arrow 24. The magnetic field established in the vicinity of the arc at the contact 6 by the arc current will act in a clockwise direction as indicated by the arrows at 25 and the magnetic field set up in the vicinity of the arc at the contact 7 by the arc current will act in counter-clockwise direction as indicated by the arrows 26. The combined magnetic field in the region of the contact 6 due, on the one hand to the coil current and on the other hand to the arc current, will have a component acting at right angles to the path of the arc as indicated by the arrow 27. Similarly the combined magnetic field in the region of the contact 7, due to the current in the coil 21 and the arc current will have a component acting at right angles to the path of the arc as indicated by the arrow 28. With this arrangement the longitudinal axis of the coil 21 may be considered as being substantially in a plane with the longitudinal axis of the arc.

Accordingly the arc at the contact 6 will tend to move bodily away from the contacts 4 and 6 in the direction indicated by the arrow 27 and the arc at the contact 7 will tend to move bodily away from the contacts 5 and 7 in the direction indicated by the arrow 28.

Each of the arc extinguishing structures 14 and 15 (Fig. 1) associated with the stationary contacts 4 and 5 may conveniently be in the form illustrated and described in the aforesaid United States patent and application.

In practice, these structures will be arranged so that the transverse passages (designated 13 in

the aforesaid United States Patent No. 1,902,507 and designated 6 and 15 in the aforesaid United States application Serial No. 622,780) through which a blast of liquid is caused to pass during the opening movement of the moving contact, extend in the direction along which the arc tends to move under the action of the forces set up as aforesaid, and in the same sense. Thus the blast of liquid which is directed on the arc at each moving contact will act to assist in moving the arc bodily away from the circuit interrupter contacts into the surrounding body of liquid in which the contacts are immersed.

In another form of the arc extinguishing structures 14 and 15, which is illustrated in Figs. 2, 4, 15 and 5, the structure comprises a nest of flat grids or plates 30, 31 (Fig. 4) of refractory insulating material arranged alternately in parallel planes and secured together by supporting rods 32 which will be adapted to be secured to the stationary contact with which the structure is to be associated. In the construction illustrated in Fig. 2, the grid 30 comprises two flat plates 33 and 34, as shown, the plate 33 is formed with a recess 35 and both plates 33 and 34 recessed jointly to 25 provide a substantially circular opening 36 communicating on the one hand with the opening 35 through a restriction 37 and on the other hand through a further restriction 38 with a flared opening 39.

As shown in Fig. 5, the plate 31 is formed with a recess 40 of substantially the same shape as the recess 35 in the plate 30. In the assembled structure, the grids 30 and 31 are mounted on the supporting rods 32 with the several recesses 35 aligned with the recesses 40 so as to form an extended passage along which the moving contact will move during the opening and closing of the circuit interrupter. This passage will communicate with a series of shorter parallel passages formed by the aligned openings 36, through transverse passages formed by the restricted openings 37, and the said shorter passages will communicate with the flared openings 39 through transverse passages formed by the restricted openings 38.

By this construction a plurality of passages disposed transversely of the direction of movement of the moving contact, and thereby transversely of the path of the arc, is provided along which the arc gases will be caused to pass out of the structure and into the ambient liquid under the action of aforesaid magnetic fields. The shaping of the grids to form restrictions as described will produce turbulence and liquid blast effects tending to increase the efficiency of the arc extinguishing means.

It should be understood that my invention is not limited to specific details of construction and arrangement thereof herein illustrated, and that changes and modifications may occur to one skilled in the art without departing from the spirit of my invention.

I claim:—

1. A liquid immersed circuit interrupter comprising a pair of stationary contacts, a vertically movable bridging member arranged to interconnect said contacts, a coil carried by said bridging member and electrically connected to contact portions at opposite ends thereof so as to 65 constitute the bridging conductor, the longitudinal axis of said coil extending transversely of the path of movement of said bridging member and of the arcs formed between said stationary contacts and the aforesaid coacting contact portions. 75

2. A liquid immersed circuit interrupter comprising stationary contact structure, coacting movable contact structure, said stationary contact structure forming a confining passage 5 through which the arc is drawn and communicating pressure exhaust passages disposed transversely thereof, and a coil carried by said movable contact structure and connected in the circuit to be interrupted for producing a magnetic field, said coil arranged so that the resultant force component produced by the reacting magnetic fields of the coil and arc currents tends to urge said arc from said confining passage through said exhaust passage.
- 15 3. A liquid immersed circuit interrupter comprising stationary contact structure, coacting movable contact structure, said stationary structure forming an arc passage through which the arc is drawn and communicating pressure exhaust passages leading laterally from said arc passage, and electromagnetic means connected 5 in the circuit to be interrupted coacting with said contact structure arranged so that the resultant force component produced by the reacting magnetic fields of said electromagnetic means and the arc currents respectively tends to urge the 10 arc from said arc passage in a lateral direction through said exhaust passage in accordance with progressive opening movement of said contact structure.
